UNITED STATES PATENT OFFICE.

ALOIS BERNHARD FISCHL, OF DRESDEN, GERMANY.

STRAW-COVERING MATERIAL FOR MOUTHPIECES OF CIGARETTES AND THE LIKE.

1,241,840.

Specification of Letters Patent.

Patented Oct. 2, 1917.

Application filed December 16, 1913. Serial No. 806,993.

To all whom it may concern:

Be it known that I, ALOIS BERNHARD FISCHL, a citizen of the Empire of Austria, residing at Dresden, Germany, have invented a new and useful Improvement in Straw-Covering Material for Mouthpieces of Cigarettes and the like, of which the following description and drawings are a full and accurate specification.

10 My invention relates to mouthpieces for cigarettes composed of straw, and consists in a novel material therefor, consisting of bands of silk paper covered with parallel, slitted and flattened straw stalks, bound together by means of adhesive plates or tabs, and in a process for making the same.

Cigarettes with a mouthpiece covering made of slitted and flattened straw stalks have been made for seventeen years and have 20 been in great demand since the expiration of the patent relating thereto. Neither the inventor, nor his coworkers, however, have been able to attach the straw covering to the wrapper of the cigarette save by hand, although cork coverings have been made in 25 rolled-up strips on bobbins, and these coverings have been handled by means of machinery. The starting or raw material could not 30 be used because it is rather brittle, would not roll uniformly, and its edges were easily torn, and also because the raw material comes into commerce in pieces of rather small sizes.

This raw material consists of little leaves 35 of silk paper, upon which are pasted slitted, flattened and parallel straw stalks. Mechanical production of the raw material has not been possible, up to the present, while production by hand is too expensive. Mechanical production would, however, not be 40 very useful, for the dimensions of the straw covered leaf of silk paper is limited in one direction by the knots of the straw stalks. The procurable straw stalks are ordinarily 45 not longer than about eighteen centimeters. The dimension in the other direction is not limited, that is, endless strips of paper could be pasted.

After many efforts the inventor has been 50 able to produce spools or bobbins, for utilizing the raw material found in commerce, which spools are adapted for mechanical operation in a cigarette machine or in a machine for covering of the wrapper paper, 55 somewhat like the bobbins adapted for cork or gold leaf coverings.

Cigarettes with straw mouthpieces are thus produced, which are far superior to the hand-made product in cleanliness and in uniform appearance. The superiority of 60 the mechanically made product consists in having the fibers of the straw completely joined to the circular or elliptical periphery of the cigarette and parallel to the axis, and also in producing a uniform reflection of the 65 light. On the other hand the cigarettes with hand made mouthpieces are inferior in the fitting to the periphery of the cigarette and in the parallelism of the threads of the straw, and they do not reflect the light in 70 all directions in a uniform manner.

It is old to overcome the brittleness of the starting material by pulling it over an edge on the side of the silk paper, as for example, when a rolled-up drawing is pulled over the 75 edge of a table, to flatten it. However, a perfect and uniform flexibility or suppleness of the straw covered leaves could not be thus obtained, and the further manipulation of the material so treated seemed impossible. 80 This, however, has been obtained by the inventor, after many failures, in a manner that will be set forth in the disclosure of the machine. It was determined to fasten together the before-mentioned short pieces of 85 the straw pasted paper, along their long sides, by means of adhesives, tabs or plates, or on a long tape. An overlapping pasting of the pieces did not appear suitable because of the thickening at the place of pasting, while the adhesive material could not 90 hold on the outer surfaces of the straw stalks, which were coated with silicic acid. Besides, the overlapping would still further lesson the short single pieces. Besides, the 95 above-mentioned treatment for the first time permitted the possibility of fastening the single pieces end to end, for rendering them pliant or elastic. These lateral edges lie so perfectly flat and the brittleness of the stalk 100 pieces is so perfectly overcome at the ends, that two lateral edges may be joined together on the adhesive tab or plate and the cigarettes which are not subjected to pressure, are not worthless. A groove resulting 105 from a circumferential tear is not injurious, if the torn stalk is not readily distinguishable through its color.

The drawings show different views of the machine for carrying out the process and 110 making the material.

Figure 1 is a front view,

- Fig. 2 is a plan view,
- Fig. 3 a front perpendicular cross-section,
- Fig. 4 a detail view of the spur-wheel drive,
- 5 Fig. 5 shows a detail view of the pasting and winding spool, and
- Fig. 6 shows the winding spool *m*, partially unwound.
- 10 The pieces of the straw covered silk paper are designated by *a*, *b*, *c*, *d*, and one of the pasting tags or plates is designated on the unwound part by *e*. The strip is wound upon the paste core *f*. The winding up occurs in the direction of the breadth of the 15 stalks as they are found in the starting material of commerce. The cutting to get the covering strips shown in Fig. 5 can be done in the well-known manner, either before, during, or after the winding up.
- 20 The remaining figures show the machine for making the material pliant.

Both rollers 1 and 2 are covered with soft rubber or the like. They are uniformly driven by the pulley 3 and the spur wheels 25 designated in Fig. 4 as 5, 6, 7. The number of teeth of the spur wheels 5 and 7 is different, so that the roller 2 revolves somewhat more quickly than the roller 1 and thereby creates a pulling effect upon the 30 material. Between both rollers is the bolt 8; having a sharp-edged lower surface, perpendicular to both side faces. If the bolt 8 is pulled down by means of lever 9, bar 10, and a foot rest not shown, or the like, as 35 far as the limiting screw 11 permits, both edges of the faces of the bolt press somewhat into the soft roller covering.

The straw covered silk paper is driven over the table 12, so that its front edge is 40 gripped by the bolt 8. The straw threads are thereby pulled laterally over the table 12, the silk paper being above and the straw being below, the straw being thus joined to the paper in this instance before it is rendered pliant.

As the edges of the bolt 8 press somewhat into the roller covers, the effect is not the same as if a leaf of the material is merely drawn over a sharp edge. The effect may 50 also be produced by one roller. Fiber after fiber of each straw stalk is successively pressed into the roller cover, and led around

the sharp edges of the bolt 8, so that the binding web between the consecutive fibers is powerfully pulled and thus loosened and 55 its brittleness is destroyed. This is repeated at the second roller. At the same time another pulling and stretching of the material occurs between the rollers. The combined result is a perfect and uniform pliancy 60 of the raw material, and besides a handsome silk-like polish is given to the straw covering.

When these straw stalks are now wound about the cigarette, so as to form mouthpieces, the fibers of the straw will lie parallel to the axis of the cigarette, and conform perfectly to its cross-section, since the connection between the consecutive fibers has been loosened, as above stated. After the 70 raw material has been thus rendered pliant, the covering strips of straw for making the mouthpieces are cut into proper widths to be fed into the cigarette-making machine.

Having thus described my invention, what 75 I desire to secure by Letters Patent is:—

1. A straw covering for mouthpieces of cigarettes, consisting of parallel, slitted, and flattened straw stalks, said flattened stalks being fastened together by adhesive means, 80 and having the binding material between the fibers of the stalks stretched and loosened, the width of said strip being such that it can be directly fed into the cigarette 85 making machine.

2. A straw covering for mouthpieces of cigarettes, consisting of a tape, said tape having fastened thereto slitted and flattened straw stalks, the adjacent edges of said stalks touching each other without 90 over-lapping, said stalks being arranged so that their fibers are parallel, and having the binding web between said fibers stretched and loosened, the width of said tape being such that it can be fed directly into the 95 cigarette making machine.

In testimony that I claim the foregoing as my invention, I have signed my name in presence of two subscribing witnesses.

ALOIS BERNHARD FISCHL.
